UNITED STATES PATENT OFFICE.

HENRY C. OSBORN, OF CLEVELAND, OHIO, ASSIGNOR TO THE AMERICAN MULTIGRAPH COMPANY, OF CLEVELAND, OHIO, A CORPORATION OF OHIO.

PLATEN RELEASE FOR PRINTING PRESSES.

Application filed February 5, 1923. Serial No. 616,924.

This invention relates to mechanism for controlling the co-ordination of two co-operating members in such manner that the control is determined by the movement or non-movement of the article to be acted upon rather than by the presence or absence of such article. Numerous safety or throw-out mechanism have been designed for various types of machinery, operative on the principle of testing for the presence or absence of the article to be acted on and throwing out of connection, or failing to throw into connection, the actuating mechanism when the article is absent. Now such principle of operation has limitations and is frequently non-effective because it is either necessary to arrange the mechanism so that the testing is made with the article in its operative position—frequently impracticable from a mechanical standpoint or if the testing is as usual made in advance thereof, failure of the article to move from the testing position to the active position has no controlling effect and a faulty operation results. According to the principle of my invention, the mechanism is inactive even though the article be present at the testing point unless such article is actually moving into the operative position. My means for controlling the operation dependent on the movement or non-movement of the article is adaptable for a variety of machines, among which may be mentioned impressing mechanisms of various sorts where a coaction of the impressing members in the absence of the article is to be avoided. As an illustration of such impressing mechanism, I may cite the printing press where the platen should be maintained out of contact with the type bed whenever the feeding mechanism fails to present paper for printing, thus avoiding the inking of the platen surface and the resultant offset printing on the back of a subsequent sheet. A frequent form of platen release operative upon failure in the feeding of paper, comprises fingers which test for the presence or absence of paper, the fingers being restrained by the paper when present but allowed to move into another position when the paper is absent, there being mechanism actuated by such movement to release the platen. With such mechanisms difficulty has been experienced in making the mechanism sensitive enough not to injure thin

paper and respond properly to the presence or absence thereof, and still have force enough to actuate the platen moving mechanism.

By a proper embodiment of my invention I control the positioning of the platen, not by the presence or absence of the paper, but by reason of the movement of the paper. I find that by this principle I can obtain satisfactory results with all grades of paper, and moreover, even though the paper be properly fed to the platen, unless it be actually gripped thereby the platen is maintained in idle position.

My invention may be adapted, for example, for bed and cylinder presses, and is illustrated herein as applied to a press of the type wherein the cylinder or platen makes two rotations to each complete reciprocation of the bed, one rotation corresponding to the printing stroke and the next rotation effecting the delivery of the printed sheet while the bed is returning to initial position. The invention is hereinafter more fully explained in connection with the drawings, and the essential features are summarized in the claims.

In the drawings, Fig. 1 is a side elevation of a bed and cylinder press employing my invention; Fig. 2 is a plan of the portion of the machine embodying my invention; Fig. 3 is a vertical central section through the platen on a larger scale, as indicated by the line 3-3 on Fig. 2; Fig. 4 is a detail in side elevation of mechanism adjacent to the forward end of the paper table looking in the opposite direction from Fig. 3, being a section as indicated by the line 4-4 in Fig. 2; Fig. 5 is a transverse vertical section along the platen shaft; Fig. 6 is a detail of the cam and lever mechanism which controls the shaft of the platen; Fig. 7 is a detail in front elevation of the mechanism shown in Fig. 6; Fig. 8 is a sectional end view of a portion of the platen, illustrating the mechanism for controlling the gripper.

The bed and cylinder press shown in the drawings to illustrate my platen release mechanism is the invention of Lawrence H. Morse and shown in his application No. 602,161 filed November 20, 1922, and reference should be made to that application for claims on any features of the construction shown not concerned with the automatic release of the platen. I will first briefly de-

scribe the press shown in order that the operation of my mechanism may be clearly understood, but it should be particularly noted that my invention is not confined to such bed and cylinder press.

In Figs. 1, 2, 3 and 5, 10 indicates the frame of the press and 11 a reciprocating type bed carrying a suitable printing form as 12 and guided by said frame and slideable on suitable interposed rollers 13. Rising from the frame are standards 14 in which are journaled the eccentric ends 15 of a shaft 16 on which the platen 17 is journaled. I have illustrated a sprocket chain 18 connected with a block 19 slideable in vertical ways 20 on the type bed as a means for reciprocating such bed. I have shown a sprocket chain 21 for rotating the platen. I have also indicated at 22, 23 and 24 suitable inking mechanism, a paper supply table, and a delivery table, respectively. The paper ejecting mechanism, the mechanism for operating the inker, and various other mechanisms of a complete press are omitted.

Keyed on one end of the eccentrically mounted platen shaft 16 is an arm 26 which is connected by an adjustable link 27 with a rock arm 28, the other end of which is rigidly mounted on the outer end of a rock shaft 29 journaled in the standard 14. On the inner end of this rock shaft 29 is the lever 30 which carries a roller 31 which is adapted to be engaged and operated by a cam 32 on the reciprocating type bed 11. Accordingly, when this cam acts on the roller the platen shaft is turned in the direction to lower the platen into position to coact with the type for printing. When the cam clears the roller 31 a spring 33 returns the parts to initial position thereby elevating the platen to idle position.

The mechanism described turns the platen to active position once every complete reciprocation of the type bed, but whether the platen remains down or not depends on whether the arm 26 becomes latched; otherwise the spring 33 immediately returns the platen to idle position. Fig. 1 shows at 35 a latch adapted to coact with the arm 26 and hold the platen active, the latch being shown in this figure as idle, being retained elevated by a locking dog 40. This dog is acted on by my mechanism hereinafter described, and is thereby raised free from the latch whenever the paper is being properly drawn along by the platen, and when so raised a spring 41 lowers the latch 35 into position to engage the arm 26, thereby retaining the platen in its active position.

At the end of the printing stroke another cam 45 on the type bed coacts with a roller 46 on the arm 47 which acts to compress a spring 48 between the arm and a shoulder on a rod 49 connected to the latch 35. Such compression does not instantly cause the re-

lease of the latch 35 by reason of the friction between its end and the arm 26, but immediately following the compression of the spring 48 the cam 45 acts on the roller 31 on the arm 30 to turn the arm 26 sufficiently to free the latch 35, and thereupon the spring 48 instantly withdraws the latch 35 from the path of the arm 26, and then as soon as the cam 45 clears the roller 31 the spring 33 returns the platen to idle position.

The paper to be fed (A in Fig. 3) is shown as resting on a paper table 23 and is shoved manually or otherwise toward the right in Fig. 3, a sheet at a time, with its front portion passing between guides 52 and 53 until the front edge abuts a series of stop fingers 54 above the platen. The platen is provided with suitable gripping fingers 60 carried on a rocking bar 61 which is controlled by suitable mechanism to cause the fingers to swing away from the platen following the printing stroke to discharge the paper and thereafter just after the fingers pass under the edge of the sheet the fingers swing rapidly toward the platen and thus grip the sheet.

The gripper bar 61 is mounted on a shaft 63 which is journaled in the platen and extends beyond it carrying a pinion 65. This pinion, as shown in Fig. 8, meshes with a segment gear 66 mounted on the drum. The segment carries a roller 67 which coacts with a stationary cam 68 surrounding the axis of rotation. A spring 69 tends to draw the roller toward the cam and such movement rotates the gripper shaft in a direction to carry the fingers away from the drum. The cam is so shaped that before the gripper comes adjacent to the edge of the paper, the gripper is released by the cam and rocked by the spring 69 into open position. Then, just after the gripper fingers pass the edge of the paper, the cam acting on the roller causes the gripper fingers to move rapidly toward the drum, this movement bringing the fingers toward the paper faster than the rotation of the drum carries the gripper away from the paper, the fingers thus swinging between the separated members 54 of the paper stop and gripping the paper between the fingers 60 and the drum so that the paper is drawn along by the rotation of the drum.

During the printing stroke, the gripper is latched closed by suitable mechanism not shown, so that the roller cannot approach the cam and open the gripper before it is desired to release the paper. This latch is controlled by suitable two-to-one gearing hereinafter mentioned, whereby it operates on every alternate rotation of the platen.

The mechanism so far described, with the exception of the locking dog 40 for the platen latch 35, is independent of my invention. As hereinbefore stated, my invention

provides means acting on the locking dog 40, and moved automatically by the travel of the paper when gripped, to move the dog into position to release the latch to 5 allow the platen to function. This mechanism will now be described.

70 designates a roller flattened on one side mounted on a shaft 71 journaled in arms 72 and 73 which are keyed to a rock shaft 74. 10 This rock shaft 74 is shown as mounted in a pair of movable frame members 75 and 76 which are shown as being pivoted to allow ready access to the platen. On the end of the shaft 74 is an arm 77 carrying a roller 15 78 which coacts with a cam 79. This cam is on the hub of a gear 80 which meshes with a driving gear 81 having half the diameter of the gear 80; this driving gear rotating with the platen, and being shown as 20 mounted on the hub of the driving gear 83 of the platen.

It results from the mechanism just described that on every alternate rotation of the platen, the cam 79 acting on the roller 25 78 through the rock shafts and rock arms mentioned, lowers the roller 70 into engagement with the paper in opposition to the plate 52 which is below the paper. In its idle position, the roller has its flattened face 30 substantially vertical, as indicated by broken lines in Fig. 4. When it is lowered into coaction with the plate 52, unless the paper between them is moving no action transpires, but if the paper is moving forwardly (as it 35 must be, when gripped by the gripper) the roller is thereby rotated, the lower edge forwardly, until the flattened face comes approximately horizontally, in which position it is stopped by a pin 87, Fig. 4, engaging 40 a stop pin 88. This partial rotation of the roller and its shaft 71 turns an eccentric 90 on the end of the shaft against the upstanding arm 91 of the dog 40 and thus withdraws this dog from engagement with the 45 platen retaining latch 35 against the action of the spring 41, this spring serving the double purpose of acting both on the dog and the latch.

After the cam 79 has cleared the roller 78 50 so that the paper testing roller 70 is elevated, a spring 95 returns this roller 70 to initial position. This spring is shown as connected by a link 96 with a crank pin 97 on the end of the eccentric 90. The paper having 55 turned the roller 70 far enough to carry the crank pin 97 past the dead center, the spring 95 completes the rotation of the roller as soon as the pin 87 clears the pin 88, upon the elevation of the roller.

60 It will be seen from the mechanism described, that periodically, following the point in the cycle when the paper should be gripped, a testing is made for the movement of such paper. If the paper is not both present and moving, the action is idle and the

platen latch remains locked, so that when the reciprocating bed turns the platen down it will not remain down but will immediately return to idle position. On the other hand, if the paper is present and moving, 70 then the dog is moved to release the latch and the platen thus becomes latched in active position.

The testing of the paper by reason of its movement rather than by its presence or 75 absence, is an important characteristic, since it prevents action whenever the gripper for any reason misses the paper, even though it may be properly fed by hand. The operation is rapid and efficient and is independent 80 of the kind of paper employed and has no tendency to injure the paper. The mechanism is simple and may be readily embodied in a press without interfering with the other mechanisms. 85

While I have illustrated my invention as applied to a printing press, and have described such press and the mechanism adapted thereto with considerable detail, it should be noted that I do not intend to 90 limit myself to the control of printing presses, as my essential invention is adaptable for various types of machinery acting on the articles fed to an active position. Certain of the appended claims are on their 95 face limited to the combination with a printing mechanism, but as to others, it is not intended to so limit them except in cases where the prior art so requires.

I claim:

1. The combination of two cooperating members adapted to act on interposed material, means for drawing such material between the members, a shiftable rotative testing device, means for shifting it into engagement with the material, and mechanism axially connected with said device and driven by its rotation while in such engagement to control the mutual presentation of said members to each other. 105

2. In a machine of the character described, the combination of a flat type bed, a platen, a gripper on the platen, a paper table, a testing device located adjacent the path of the paper from the table to the gripper, and comprising a member mounted on a bodily shiftable rotative shaft, periodically acting mechanism for shifting the shaft to move said member into engagement with the paper, whereby said shaft is given a rotative movement caused by the traveling paper, a cam on the shaft, and mechanism actuated by the cam for controlling the mutual presentation of the platen and bed. 115

3. The combination of a printing member, a platen, latch mechanism adapted to hold the same in coaction, mechanism adapted to restrain the latching mechanism from such action, means for gripping and drawing the paper and means actuated by frictional en- 125

- gagement with the paper when gripped for causing said restraining mechanism to release said latching mechanism.
4. The combination, with a type bed and platen, means for causing the paper to engage and move with the platen of a roller adapted to engage the paper and be turned on its axis when such paper moves, and mechanism actuated by the turning of said roller for causing the platen and type bed to be maintained in coaction.
5. The combination of a printing member, a platen having a gripper, mechanism to change the presentation of the printing member and platen, latching mechanism adapted to maintain the printing member and platen in printing coaction, mechanism for holding the latching mechanism inactive, and mechanism operated by the movement of paper gripped by the platen for causing such holding mechanism to free said latch.
6. The combination of a type bed, a shiftable roller platen having a gripper, mechanism to shift the platen to and from coaction with the type bed, a latch adapted to hold the platen in its active position, mechanism for holding the latch inactive, and mechanism operated by the movement of paper gripped by the platen for causing said holding mechanism to free said latch.
7. The combination with a printing member and a shiftable platen adapted to coact therewith, of mechanism for moving paper into printing position between said member and platen, mechanism operating periodically to bring the platen into active position with relation to the printing member and then release it, a latch adapted to maintain the platen in such active position when released by the moving mechanism, and paper testing mechanism adapted to control the latch and including a member moved by the advancing paper while under the control of the first mentioned mechanism.
8. The combination with a printing member and platen, one of which is shiftable into and out of coaction with the other, means on the platen for gripping paper, a roller adapted to engage such gripped paper and be turned thereby, means for moving the roller into and out of engagement with the paper, and mechanism actuated by the turning of said roller when in engagement with said paper for controlling the presentation of the platen and type member.
9. The combination with a type bed and a shiftable roller platen adapted to coact therewith, of mechanism for advancing paper to be printed, mechanism operating periodically to bring the platen into active position with relation to the type bed and then release it, a latch adapted to maintain the platen in such active position when released by the moving mechanism, a restraining device for holding the latch idle, a roller, means for moving it into engagement with the paper being advanced, and mechanism operated by the turning of the roller, for moving the restraining device to release the latch.
10. The combination of a reciprocating type bed, a shiftable platen adapted to coact therewith, cam mechanism between the type bed and platen for periodically shifting the platen into coaction with the type bed, mechanism for latching the platen in such coaction, and restraining means for the latching mechanism released by the travel of paper to be printed.
11. The combination of a reciprocating type bed, a shiftable roller platen, a paper gripper on the platen, mechanism for periodically shifting the platen into and out of coaction with the bed, latch mechanism adapted to retain it in such coaction, a restraining device for the latch mechanism, a device adapted to engage the gripped paper and be operated by the travel thereof for causing said restraining device to release the latch mechanism.
12. The combination of a reciprocating type bed, a shiftable roller platen coacting therewith, mechanism for moving the platen periodically into and out of coaction with the type bed, a latch mechanism for holding it in coaction, a restraining device for holding the latch mechanism in idle position, a paper gripper on the platen, a roller adapted to be brought periodically into engagement with the paper gripped by the gripper, and means controlled by the turning of such roller by reason of the travel of the paper to cause the restraining device to release the latch mechanism.
13. The combination of a printing member, an eccentrically mounted platen, mechanism for periodically turning such mounting to present the platen to the printing member, a roller adapted to engage paper being fed by the platen, and means controlled by the rotation of such roller for determining the position of the eccentric mounting on the platen.
14. The combination of a printing member, an eccentrically mounted platen, mechanism for periodically turning such mounting to present the platen to the printing member, a roller, means for advancing paper toward printing position, means for moving the roller into engagement with a sheet of paper after it has contacted with the platen, and means controlled by the rotation of such roller for determining the position of the eccentric mounting on the platen.
15. The combination of a printing member, an eccentrically mounted platen coacting therewith, means for periodically turning the eccentric mounting to present the platen to the printing member, latch mechanism for holding it in this position, a roller

adapted to engage paper being drawn to the printing position by the platen, and means whereby the rotation of said roller releases the latch mechanism to enable it to maintain the platen in its active position.

16. The combination of a printing member, a roller platen adapted to coat therewith, means for causing the platen and printing member to assume active or inactive mutual positions, a gripper on the platen, a paper table along which paper may be fed to the gripper, a roller, means for moving it into engagement with the paper between the table and gripper after the gripper has engaged the paper, and means controlled by the turning of the roller for controlling such mutual position.

17. The combination of a printing member, a roller platen adapted to coat therewith, means for periodically bringing the platen and printing member into coaction, latch mechanism for maintaining this coaction, a paper gripper on the platen, a paper table along which paper may be fed to the gripper, a device adapted to engage the paper between the table and gripper and being moved by the travel of the paper when gripped, and means whereby the movement of said device releases the latch mechanism to enable it to maintain the platen in its active position.

In testimony whereof, I hereunto affix my signature.

HENRY C. OSBORN.
